UNITED STATES PATENT OFFICE

2,615,456

DIESEL ENGINE FILTER CLEANER

Earl E. Galusha, Salt Lake City, Utah, assignor, by direct and mesne assignments, of two-fifths to William Fötés and one-fifth to Horace C. Beck, both of Salt Lake City, Utah

Application October 12, 1950, Serial No. 189,806

7 Claims. (Cl. 134—140)

1

This invention relates to improvements in filter core cleaners.

An object of this invention is to provide an improved structural assembly for retaining and cleaning a filter core, preferably of the type which is used in diesel engine fuel systems.

Another object of this invention is to provide the entire cleaning assembly on the top or cover of a tank, the tank being adapted to contain a cleaning fluid of standard type, which cleaning fluid is drawn by means of a gear pump into a pressure chamber, the pressure chamber having communication with the interior of a filter core which is arranged in a core chamber, whereby the cleaning fluid after having served its purpose in connection with the core is permitted to drop through a drain into the tank.

Another object of this invention is to provide an improved means of retaining the filter core on the spindle of the device.

Ancillary objects and features of importance will become apparent in following the description of the illustrated form of the invention.

In the drawings:

Figure 1 is a longitudinal sectional view of the device, portions being shown in elevation;

Figure 2 is a longitudinal sectional view of the casing which is disposed upon the top of the tank, various operative elements of the device being disposed therein;

Figure 3 is a transverse sectional view taken substantially along the line 3—3 of Figure 2 and in the direction of the arrows;

Figure 4 is a transverse sectional view showing the pressure chamber assembly and taken substantially along the line 4—4 of Figure 2 and in the direction of the arrows;

Figure 5 is a sectional view taken along the line 5—5 of Figure 2 and in the direction of the arrows illustrating principally the gear pump, and;

Figure 6 is a sectional view taken substantially along the line 6—6 of Figure 2 and in the direction of the arrows showing primarily the carrier bearing for the standard oil filter core.

In carrying out this invention I have provided a tank or receptacle 10 which has a surface drain valve 14 adjacent but spaced from the top or cover 16 of the tank. The cover is provided with a flange 18 along its edge which is arranged to seat upon the lip 20 near the top of the tank 10.

Located entirely upon the top or cover 16 of the tank is an assembly for holding, rotating and cleaning a filter core, for example that standard core 22 illustrated in Figure 2. By virtue of having all of the operative elements located directly on the tank 10, for example on the mounting plate 24 of the cover 16, there need not be any separation of any of the parts and need not be any special supports other than those which are connected directly with the tank 10.

2

A motor 26 is used to operate the gear pump 28, the gear pump being of standard description including the driving shaft 30 as well as the spindle 32, the shaft 30 and the spindle 32 supporting the gears 34 and 36 of the pump. As noted from inspection of Figure 5 the gear 34 is keyed as at 38 to the shaft 30, and the gears 34 and 36 are located in the casing or pump housing 40.

The shaft 30 is connected to the motor shaft 42 by means of a standard coupling 44 and hence, upon operation of the motor 26 the gear pump 28 becomes operative. A conduit generally indicated at 46 extends from within the tank 10 to the gear pump 28 and then from the gear pump 28 into the pressure chamber 48. This pressure chamber is defined by a casing 50 which may be a casting with a removable end plate 52 thereon. This pressure chamber is adapted to receive fluid under pressure through the conduit 46 and to allow that fluid to be passed into the filter core 22.

As disclosed in Figure 2 the shaft 30 passes through standard oil seals 49 and 51 on opposite sides of the gear pump 28 and the shaft 30 has a carrier bearing 54 keyed thereto. This carrier bearing is in the form of a spider with a plurality of arms 56 extending therefrom which are arranged to fit over the inner end of the core 22. A groove 58 is formed in the outer end of each arm in order to seat another part of the filter 22. There is a ring 60 at the outer ends of the arms 56 integrally connecting them and this ring constitutes a bearing which is disposed in a central opening or aperture 62 in the vertical partition 64. This partition separates the casing 50 into the pressure chamber 48 and the filter core supporting chamber 66.

There is a sump 70 formed at the bottom of the filter core chamber and a small outlet pipe 72 is connected therewith and opens into a chamber 74 defined by the portion 73 in the tank 10. The chamber 74 has a filter 75 therein through which the cleaning fluid must flow since the pipe 72 extends a considerable distance into it. The outlet member 77 for the filtered fluid is located in the partition 73 and is arranged to conduct the filtered fluid from the chamber 74 into the remainder of the tank 10.

In order to hold the filter core 22 on the spindle 74 in the core chamber 66, an improved centering device is used. A standard oil seal 78 is connected to the removable closure 80 of the casing 50 and has a shank 82 mounted for rotation therein. There is a tapered end 84 on this spindle arranged to be disposed in the central opening 86 of the collar 88. This collar is threaded on its outer periphery to accommodate the nut 90, the function of the nut being to abut the outer end of the oil filter 22.

A threaded extension 92 of the spindle 74 is disposed in a threaded bore 96 of the spindle 82.

Therefore when the spindle is tightened on the extension 92 the tapered shank or spindle is held in place in the oil seal 78. As the shaft 30 is rotated the threads on the threaded shank or extension 92 pull the spindle 82 so that the tapered end 84 is pulled firmly in the central aperture 86 of the collar 88. This holds the filter core 22 fixed firmly around the spindle 74 which is in fact, an extension of the shaft 30.

In operation the motor 26 is set in motion after a core has been inserted through the opening of the casing 50 and held in place through the expedient of the tapered end 84 on the spindle or shank 82. Inasmuch as operation of the motor 26 causes the gear pump 28 to be operative, fluid is raised from the tank 10 and introduced under pressure into the pressure chamber 48. This fluid has no place to discharge except between the arms 56 of the carrier bearing 54. By passing into the inner sleeve of the core 22 under pressure, the fluid passes through all of the openings, screens and the like of the filter core while it is being rotated on the spindle 74. In order to break the flow of fluid in the core chamber 66 and in order to cause a swirling action of the liquid, the baffles 98 which are located longitudinally within the core chamber 66 deflect the fluid appropriately and properly.

Then the fluid after it has served its purpose in the core chamber 66 is discharged into the chamber 71 of the tank 10 through the sump 70 and the outlet member 72.

When it is necessary to draw the top fluid from the tank 10, the valve 14 is used. When it is necessary to remove the sediment or clean the tank, the plug 12 is used.

Having described the invention, what is claimed as new is:

1. In a filter core cleaner, a liquid tank having a top and means disposed on said top for holding a filter core and circulating liquid from said tank through it, said means comprising a motor driven pump with an inlet member disposed in said tank, said pump having a shaft and an outlet; and a casing having a pressure chamber, a filter core end carrier bearing having liquid passages therein connected to said pump outlet, said bearing being fixed to said shaft, and means for supporting the other end of the filter core.

2. In a filter core cleaner, a liquid tank having a top and means disposed on said top for holding a filter core and circulating liquid from said tank through it; said means comprising a motor driven pump with an inlet member disposed in said tank, said pump having a shaft and an outlet; and a casing having a pressure chamber, a filter core end carrier bearing having liquid passages therein connected to said pump outlet, said bearing being fixed to said shaft, means for supporting the other end of the filter core including a collar attached to said shaft, and means adjustable axially of said shaft to hold said collar fixed on said shaft.

3. In a filter core washer, a liquid tank, means disposed on said tank for holding and washing a filter core, said means comprising a motor, a pump driven by said motor, a casing with a partition dividing said casing into a pressure chamber and a core holding chamber, a liquid conductor extending from said tank to said pump and from said pump to said pressure chamber, said partition having an opening, a shaft disposed in said casing and passed through said opening, said shaft being connected at one end to said pump, a core carrier bearing secured to

5 said shaft a distance from said end of said shaft and arranged to hold one end of the core in said opening, said bearing having liquid passages therein through which liquid under pressure from said pressure chamber is adapted to pass, and means carried by said casing for partially supporting the core in said core chamber.

4. In a filter core washer, a liquid tank, means disposed on said tank for holding and washing a filter core, said means comprising a motor, a pump driven by said motor, a casing with a partition dividing said casing into a pressure chamber and a core holding chamber, a liquid conductor extending from said tank to said pump and from said pump to said pressure chamber, said partition having an opening, a shaft disposed in said casing and passed through said opening, said shaft being connected at one end to said pump, a core carrier bearing secured to said shaft a distance from said end of said shaft and arranged to hold one end of the core in said opening, said bearing having liquid passages therein through which liquid under pressure from said pressure chamber is adapted to pass and means carried by said casing for partially supporting the core in said core chamber, said last mentioned means including a collar disposed on said shaft, and adjustable means for retaining said collar on said shaft in selected position axially of said shaft.

5. In a filter core washer, a liquid tank, means disposed on said tank for holding and washing a filter core, said means comprising a motor, a pump driven by said motor, a casing with a partition dividing said casing into a pressure chamber and a core holding chamber, a liquid conductor extending from said tank to said pump and from said pump to said pressure chamber, said partition having an opening, a shaft disposed in said casing and passed through said opening, said shaft being connected at one end to said pump, a core carrier bearing secured to said shaft a distance from said end of said shaft and arranged to hold one end of the core in said opening, said bearing having liquid passages therein through which liquid under pressure from said pressure chamber is adapted to pass, means carried by said casing for partially supporting the core in said core chamber, said last mentioned means including a collar disposed on said shaft, said collar having an aperture, a tapered shank threaded on said shaft and in contact with the aperture of said collar, and said shank being carried by said casing.

6. The combination of claim 3 and an outlet member connected to said casing, and said outlet member opening into said core holding chamber and said tank.

7. The combination of claim 3 and said shaft constituting a part of said pump and hence being rotatable when said pump is operative, and baffles disposed in said core retaining chamber to direct the flow of liquid in said core retaining chamber.

EARL E. GALUSHA.
